CLAIM

The ornamental design for a dickey accessory with integrated hand coverings, as shown and described.

DESCRIPTION

FIG. 1 is a top front perspective view of a first embodiment of the invention;

FIG. 2 is a front elevation view of the first embodiment of the invention in a flat condition;

FIG. 3 is a rear elevation view of the first embodiment of the invention in a flat condition;

FIG. 4 is an underside perspective of the front of the first embodiment of the invention;

FIG. 5 is an underside perspective of the rear of the first embodiment of the invention;

FIG. 6 is a perspective view of the first embodiment of the invention as worn by a user;

FIG. 7 is a top front perspective view of a second embodiment of the invention;

FIG. 8 is a front elevation view of the second embodiment of the invention in a flat condition;

FIG. 9 is a rear elevation view of the second embodiment of the invention in a flat condition;

FIG. 10 is an underside perspective of the front of the second embodiment of the invention;

FIG. 11 is an underside perspective of the rear of the second embodiment of the invention; and,

FIG. 12 is a perspective view of the second embodiment of the invention as worn by a user.

The broken line showing of the neck portion, the inner surfaces, and the sleeve strips are for the purpose of illustrating portions of the article and form no part of the claimed design. The broken line showing of a human figure, cup, and garment is for the purpose of illustrating environment and forms no part of the claimed design. The dash-dot-dot broken lines define the bounds of the claimed design and form no part thereof.
